UNITED STATES PATENT OFFICE.

ALBIN L. FORSBERG, OF CHICAGO, ILLINOIS, ASSIGNOR TO THOMSON AND TAYLOR SPICE COMPANY, A CORPORATION OF ILLINOIS.

POURING-SPOUT.

1,397,952.

Specification of Letters Patent.

Patented Nov. 22, 1921.

Application filed July 30, 1919. Serial No. 314,304.

To all whom it may concern:

Be it known that I, ALBIN L. FORSBERG, a citizen of the United States, residing in Chicago, county of Cook, State of Illinois, have 5 invented new and useful Improvements in Pouring-Spouts, of which the following is a specification.

This invention relates in general to pouring-spouts for containers either of sheet 10 metal, cardboard or similar material adapted to contain salt, spices and similar substances, and has for its object primarily the provision of an improved pouring-spout which, when closed, will rest flat against the 15 upper end of the container and close the opening and which may be opened to a pouring position by a pivotal movement.

The principal object of this invention is the provision of a pouring-spout which may 20 be formed of a single sheet of suitable material, which may be quickly, easily and cheaply made, and readily installed in place on the container.

I have shown a spout embodying my inventions in the accompanying drawings in which;

Figure 1, is a top plan view of a sheet metal container with my improved pouring-spout in place in closed position.

Fig. 2, is a vertical, sectional view on the line 2—2 of Fig. 1, looking in the direction indicated by the arrows.

Fig. 3, is a top plan view of the sheet metal blank from which my improved pouring-spout is formed.

Fig. 4, is a vertical, sectional view, similar to Fig. 2, showing two of the steps in the process of attaching the pouring-spout to a sheet metal container.

Fig. 5, is a vertical, sectional view similar to Fig. 2, showing two further steps in the process of attaching the spout to a sheet metal container.

Fig. 6, is a fragmentary plan view of a container showing the opening therein, before the pouring-spout is attached.

Fig. 7, is a view similar to Fig. 2, showing a different way of fastening the pouring-spout into a container.

Fig. 8, is a vertical, sectional view similar to Fig. 2, showing my improved pouring-spout attached to a container made of cardboard or similar material.

Fig. 9, is a fragmentary view showing a slight modification of a part of the pouring-spout.

In the drawings, 1, represents the top surface of a sheet metal container A in which my improved pouring-spout is attached as hereinafter explained. In the top 1, of the 60 container, is cut a rectangular opening as indicated by 2. (See Fig. 6.) Projecting into this opening from the edge at one end thereof, is the tongue 4 which has its sides slightly beveled. Lying substantially on the 65 line which connects the tongue 4 to the edge of the opening 2, that is, at the base of the tongue 4, is made a transverse slot 6 which does not extend the entire width of the base line of the tongue 4. The edge, or lip 8 70 of the slot 6 lying farther from the end of the tongue 4, is bent inward or downward slightly more than a distance equal to the thickness of the material. (See Fig. 5.) The opposite edge or lip of the slot 6 which 75 is permitted to lie in the original plane of the metal is indicated by 9.

The pouring-spout proper is formed from a sheet metal blank as shown in Fig. 3. This blank comprises a substantially rectangular 80 shaped center portion 10 substantially the same size as the opening 2 in the top of the container with two quadrant shaped side wings 12, 12. The center portion 10 has a semi-circular projection 14 at its end 85 where the arcuate edges of the wing members 12, 12 meet it and at its opposite end has a somewhat narrower projecting rectangular shaped tongue 18, of sufficient width to enter and substantially fill the slot 90 6. The wing members 12, 12 at the ends of their arcuate edges farthest from the center portion 10 are provided with short projecting stop members 20, 20.

I will now describe the method of forming my improved spout from a blank as shown in Fig. 3, and the method of attaching it to the container. The wing members 12, 12 of the blank are bent along the edges where they join the center portion 10, as indicated by the dotted lines 22, 22 until they lie at right angles to the center portion 10. The pouring-spout is then placed as shown by the solid lines in Fig. 4, with the stops 20, 20 hooked under the edge of the opening 105 2 opposite the edge from which the tongue

4 projects. The end of the tongue 18 is then sprung slightly until it is ready to enter the slot 6; when it is in the position shown by the solid lines in Fig. 4. The tongue 18 is 5 then forced downward through the slot 6 until the pouring-spout is in the position as indicated by the dotted lines in Fig. 4. The end 14 of the center portion 10 of the pouring-spout is then pressed down through an 10 arc into the position shown in Fig. 5; that is, the spout is put into its closed position with the rectangular part 10 covering the opening 2. The effect of this movement will 15 be to bend the tongue 18 at or near its base where it joins the edge of the center portion 10, as indicated by the dotted line 30 in Fig. 3, until it is at right angles to the portion 10 as shown by the solid lines in Fig. 5. This bending is caused by the engagement 20 of the tongue 18 with the inwardly and downwardly projecting edge or lip 8 of the slot 6 and its engagement with the opposite edge 9 of the slot 6. These two edges of the slot 6, it will be seen, hold the tongue 18 in 25 a vertical position as the pouring-spout is pressed into its closed position, causing a bend at right angles on the dotted line 30 over the edge 9. It will be seen that the dotted line 30 does not lie exactly at the base 30 of the tongue 18, the exact position of the dotted line 30 where the tongue 18 will bend over the edge 9 of the slot 6 depends to some extent upon how far down into such slot the tongue 18 has been pressed when the 35 spout 14 is forced downward and also whether or not the slot 6 is in line with the base of the tongue 4 or a short distance to the side of the base line away from the end of the tongue 4. In strict practice the dotted 40 line 30, indicating the bend on the tongue 18, should lie a distance on the tongue 18 from the base of such tongue equal to the thickness of the metal used in the top 1. This bend should be in this position so that 45 when the spout is opened as shown in the dotted lines in Fig. 2, the bent portion of the tongue lying between the dotted lines 30 and 31 will project under the edge 9 of the slot 6 allowing the thickness of the metal 50 constituting such edge 9 to project up to the tongue 18 above such bent portion. If, however, the first bend of the tongue 18 takes place exactly on the base line of such tongue 18, then when the spout is opened 55 the first time, the edge 9 of the slot 6 will open such bend or "round" it a sufficient distance so that such edge 9 will remain in contact with the base of the tongue 18 and the bend in such tongue will project a slight 60 distance horizontally under such edge when the spout is in its open position. The end of the tongue 18 is then bent over the edge or lip 8 on the dotted lines indicated by 65 in Fig. 3, until it is in the position indicated 65 by the dotted lines in Fig. 5; that is, the

portion of the tongue 18 lying between the dotted line 31 and its end, is bent upwardly and away from the center portion 10 on the dotted line 31 over the edge of the inwardly projecting lip 8 until said portion lies parallel to the center portion 10 of the pouring-spout. The pouring-spout is then completed and ready for use as shown in Fig. 2, in which the solid lines show the pouring-spout in closed position, and the dotted lines show 70 it in open position. It will be noted that when the pouring-spout is in its closed position the hinged end is prevented from being pulled out by the end of the tongue 18 which projects horizontally under the downwardly bent lip 8 of the slot 6. When the pouring-spout is in its open position the hinged end is prevented from being pulled out by the portion of the tongue 18 lying 75 between the dotted lines 30 and 31 which 80 projects substantially horizontally under the edge or lip 9 of the slot 6.

The wing members 12, 12 of the pouring-spout are cut to such size that their arcuate edges will meet the corners of the opening 90 2 as the pouring-spout is opened and closed and the stop members 20, 20 project a sufficient distance to engage the under surface of the edge of the opening 2 in order to prevent the spout from being opened too far. 95 The spout is shown in its open position by the dotted lines in Fig. 2, and as there shown, the stops 20, 20 are in engagement with the under surface of the edge of the opening 2 and preventing the spout from being further opened. The part 14 as shown in Fig. 1, projects beyond the end of the opening 2 and offers a projection which may be grasped in order to assist in opening the spout. The end of this projection may be 105 bent slightly upward as shown in Fig. 9 if desired, in order to assist in affording a purchase.

In Fig. 7, I have shown a different manner of fastening the pouring-spout to the 110 container. In using this method I bend the tongue 18 on the dotted line 30 before inserting it in the container so that it is in the position shown in solid lines in Fig. 7. I then place the pouring-spout so that it is 115 in the position shown by the solid lines in Fig. 7. The next step is to force the tongue 18 down through the slot until the pouring-spout is in the position shown by the dotted lines in Fig. 7, when it is in the same position as shown by the solid lines in Fig. 5. From this point on, the method of attaching the spout is the same as the method 120 above described, namely the end of the tongue 18 is bent upwardly and away from the center portion 10 over the edge or lip 8 until it is parallel with the center portion 10 when the pouring-spout is in place and ready for use.

In Fig. 8 I have shown my improved 125

pouring-spout attached to a container B made of cardboard or similar material. I will now describe the method of attaching the spout to such a container. The spout 5 is formed in the same manner as if it were to be attached to a sheet metal container and in addition thereto, the tongue 18 is bent on the dotted lines 30 and 31 until it has the shape as shown by the solid lines 10 in Fig. 8. That is, the spout is completely formed before it is put in the opening. The opening in the cardboard container is similar in all respects to the opening in the sheet metal container as shown in Fig. 6, except that the lip or edge 8 of the slot 6 is not downwardly and inwardly bent. Such a bend could not be made in cardboard or similar material. When the container is provided with its opening and the spout is 15 completely formed the spout is ready to be inserted into the container and this is done in the following manner. The stops 20, 20 are inserted under the edge of the opening 2 in the same manner as the first step in 20 inserting the spout into a sheet metal container and the end of the tongue 18 is then brought down toward the slot 6. The two bends in the tongue 18, however, obviously will bring the end of the tongue out of line 25 with the slot 6. The pouring-spout is then moved a slight distance until the end of the tongue 18 enters the slot 6. It is obvious that the two bends in the tongue 18 will prevent it from readily going all the way in. 30 A slight pressure is then put downward on the spout and the edges of the slot 6 bent and stretched a sufficient distance until the tongue 18 snaps into place and until the portion of the tongue 18 lying between the 35 dotted lines 30 and 31 lies horizontally under the edge or lip 9 of the slot 6 as shown by the dotted lines in Fig. 8. The pouring-spout is then in position and ready for use. It is shown in its open position by the dotted 40 lines in Fig. 8 and in its closed position by the solid lines in Fig. 8.

I claim:

1. In combination with a container having an opening with a slot at or near one edge of said opening, the lip or edge of said slot 45 farther from said opening being bent inwardly, a pouring-spout formed of a center portion and two side wing portions, said center portion having a tongue at one end

thereof adapted to form a hinged joint with 55 said slot.

2. In combination with a container having an opening with a slot at or near one edge of said opening, the lip or edge of said slot 60 farther from said opening being bent inwardly, a pouring-spout comprising a center portion and two side wing members, said center portion having a projecting tongue 65 adapted to engage with said slot, said tongue being so bent as to project horizontally under one edge of the slot when the pouring-spout is in its closed position.

3. In combination with a container having an opening with a slot at or near one edge of said opening, the lip or edge of said slot 70 70 farther from said opening being bent inwardly, a pouring-spout comprising a center portion and two side wing members, said center portion having a projecting tongue 75 adapted to engage with said slot, said tongue being so bent as to project horizontally under one edge of the slot when the pouring-spout is in its open position.

4. In combination with a container having an opening with a slot at or near one edge of said opening, the lip or edge of said slot 80 85 farther from said opening being bent inwardly, a pouring-spout comprising a center portion and two side wing members, said center portion having a projecting tongue 90 90 adapted to engage with said slot, said tongue being so bent as to project horizontally under one edge of the slot when the pouring-spout is in closed position and under the opposite edge of said slot when the pouring-spout is in open position.

5. In combination with a container having an opening with a slot at or near one edge of said opening, the lip or edge of said slot 95 100 farther from said opening being bent inwardly, a pouring-spout comprising a center portion and two side wing members, said center portion having a tongue adapted to project through said slot, said tongue having two bends, the portion between said 105 bends lying substantially at right angles to the center portion and the end of the tongue beyond said bends lying substantially parallel with said center portion.

In witness whereof, I have hereunto subscribed my name this 25 day of July, 1919.

ALBIN L. FORSBERG.
